UNITED STATES PATENT OFFICE

130,532

DESIGN FOR A SACHET

Nancy Goodstein, New York, N. Y.

Application December 4, 1940, Serial No. 97,053

Term of patent 3½ years

To all whom it may concern:

Be it known that I, Nancy Goodstein, a citizen of the United States of America and resident of Borough of Manhattan, city, county, and State of New York, have invented a new, original, and ornamental Design for a Sachet, of which the following is a specification, reference being had to the accompanying drawing, forming part thereof.

In the drawing:

The figure is a perspective view of a sachet, showing my new design.

The figure shows one side of my new design for a sachet and the other side—not shown—is similar in appearance to the side shown.

The characteristic feature of my design resides in the specific ornamentation on the sachet shown.

I claim:

The ornamental design for a sachet, as shown and described.

NANCY GOODSTEIN.
